UNITED STATES PATENT OFFICE.

WILLIAM A. WHITMORE, OF NELSONVILLE, OHIO.

WATER FEED FOR BOILERS.

Application filed August 15, 1922. Serial No. 581,981.

To all whom it may concern:

Be it known that I, WILLIAM A. WHITMORE, a citizen of the United States of America, and a resident of Nelsonville, in the county of Athens and State of Ohio, have invented a new and Improved Water Feed for Boilers, of which the following is a description.

My invention relates to a feed means for steam boilers and more particularly is intended for embodiment in what is known as a return system for returning the water of condensation from heating systems where the water flows through the trap or is sufficiently cooled to be acted upon by a vacuum, or for embodiment in a feed for boilers furnishing steam for power.

The general object of the invention is to provide a feed means of the indicated type improved in various particulars with a view to simplify the construction and attaining precision of operation.

Reference is to be had to the accompanying drawings forming a part of this specification, it being understood that the drawings are merely illustrative of one example of the invention.

Figure 1 is a partly sectional side elevation of a water feed embodying my invention;

Figure 2 is an end view thereof;

Figure 3 is a transverse vertical section;

Figures 4 and 5 are cross sectional views of the float controlled valve as indicated by the lines 4—4 and 5—5 of Figure 3.

In carrying out my invention in accordance with the illustrated example, a tank 10 is provided leading to which near the top is a water inlet pipe 11 having a check valve 12. Leading outwardly from the tank at the bottom is a pipe 13 provided with a check valve 14 for conveying the feed water to the boiler (not shown).

Rising from the trap tank 10 is a stand pipe 18 connecting said tank with a steam cylinder 19 having a piston valve 20 therein. The cylinder 19 has a steam inlet 21 which in practice receives a steam pipe (not shown) leading from the boiler. The stand pipe 18 has a steam outlet 23 which is plugged as shown when only one tank 10 is employed but which may serve for a connection to an additional tank when a plurality of trap tanks are provided.

Communication is established between the

stand pipe 18 and the steam cylinder 19 through a port 25 in said stand pipe and adjacent to said port is an outlet 26 leading to an exhaust pipe 27 having a check valve 28, communication between the port 25 and outlet 26 being established through an exhaust passage 30^a in the valve 20. Said valve 20 also has a slot indicated at 20^b which in practice receives a screw or stud bolt (not shown) tapped into the side of cylinder 19 to prevent turning of the valve 20 about its axis as fully shown and described in an application filed by me July 20, 1921, Serial No. 481,019.

Steam exhaust ports 29, 29^a lead from the respective ends of cylinder 19 and connect by exhaust pipes 30, 30^a with steam inlets 31, 31^a in a valve cylinder 32, there being exhaust ports 33, 33^a diametrically opposite in said cylinder and leading to exhaust pipes 34, 34^a. Communication between the inlets 31, 31^a and the exhausts 33, 33^a is controlled by an auxiliary valve 35 turnable in said cylinder 32, said valve being formed with transverse passages 36, 36^a. Valve 35 is operated by a float 37 in the trap tank 10, the stem of the float having connection with said valve 35 at a collar 38 thereon. The piston valve 20 affords a chamber at the center continuously supplied with steam from the steam inlet 21 and from said chamber leads longitudinally through the ends of the valve minute steam slots or ports 38, 38^a for furnishing pressure to the respective ends to move the piston.

In operation when the tank 10 is emptied the float 37 is in the lower position and in moving to the lower position it will have rocked the auxiliary valve 35, thereby permitting escape of steam through the ports 29^a and 31^a and passage 36 through exhaust port 33^a and to exhaust pipe 34^a which results in the steam in cylinder 19 at the left of the piston 20 moving said piston to the right hand end of cylinder 10 (Figure 1). The valve 20 at the same time cuts off the port 25 from the inlet 21 and from the boiler pressure and connects port 25 with the atmosphere through slot 38, port 26 and exhaust pipe 27, the check valve 28 preventing air from entering the tank, thereby producing the maximum vacuum. The turnable valve 35, it will be observed, extends across the neck 18 and the casing 32 of said valve is integral with the neck which ar-

arrangement makes for compactness of the assemblage and greatly simplifies the construction.

When the tank 10 fills and float 37 is therefore at the top, the rising of the float will have established communication between the port 29 and exhaust pipe 34 through port 31, passage 36 and port 33, which at this time will be in register, the result being that the piston 20 will be caused to move to the left, thereby uncovering the passage 25 and admitting steam from the boiler through the inlet 21 and around the valve 20 through said port 25 and to tank 10 thus equalizing the pressure in the boiler and tank, whereby water will flow from the tank to the boiler by gravity it being understood that the tank 10 is elevated a sufficient height for the purpose.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A water feed apparatus including a trap tank, a steam cylinder having a steam inlet adapted to be connected with the boiler to be fed, a valve in said cylinder, ports controlled by said valve and adapted to connect said cylinder with said tank to direct steam from the cylinder to the tank for balancing the tank pressure and boiler pressure, said valve adapted also to vent the tank for permitting inflow of water to the tank, a valve casing communicating with the steam cylinder near the ends of the latter, an auxiliary valve turnable in said valve casing and

adapted to alternately open said cylinder at the respective ends to the atmosphere through said valve casing for exhausting the cylinder and causing movement of the valve therein for alternately establishing and cutting off communication between the steam cylinder and tank, and means subject to the rise and fall of water in the tank to actuate said turnable auxiliary valve.

2. A water feed apparatus including a trap tank, a neck rising from said tank, a steam cylinder supported on said neck and adapted to receive steam from the boiler to be fed, a reciprocating valve in said casing controlling communication between said steam cylinder and said neck to direct steam from the tank through said neck, said reciprocating valve adapted also to control the venting of said tank through said neck and steam cylinder, an auxiliary valve disposed in said neck beneath the steam cylinder, means connecting the steam cylinder at its ends with the auxiliary valve, and means subject to the rise and fall of water in the tank to actuate said auxiliary valve.

3. A water feed apparatus including a trap tank, a neck rising from said tank, a steam cylinder supported on said neck and adapted to receive steam from the boiler to be fed, a reciprocating valve in said casing controlling communication between said steam cylinder and said neck to direct steam from the tank through said neck, said reciprocating valve adapted also to control the venting of said tank through said neck and steam cylinder, an auxiliary valve turnably mounted in said neck, and communicating with the steam cylinder at the opposite ends of the latter, and means subject to the rise and fall of water in the tank to rock said auxiliary valve.

WILLIAM A. WHITMORE.
